US0D1012079S

(12) **United States Design Patent** (10) **Patent No.:** **US D1,012,079 S**
(45) **Date of Patent:** **** Jan. 23, 2024**

(54) **ELECTRONIC DEVICE**

- (71) Applicant: **Samsung Electronics Co., Ltd.**, Suwon-si (KR)
- (72) Inventors: **Jaewoong Chung**, Suwon-si (KR); **Duyeong Choi**, Suwon-si (KR); **Seonkeun Park**, Suwon-si (KR); **Ethan Lee**, Suwon-si (KR); **Jungwon Lee**, Suwon-si (KR); **Seungjoon Lee**, Suwon-si (KR)
- (73) Assignee: **SAMSUNG ELECTRONICS CO., LTD.**, Suwon-si (KR)
- (**) Term: **15 Years**
- (21) Appl. No.: **29/855,619**
- (22) Filed: **Oct. 5, 2022**

Related U.S. Application Data

- (62) Division of application No. 29/775,578, filed on Mar. 24, 2021, now Pat. No. Des. 966,259.

(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the figures illustrate portions of the electronic device that form no part of the claimed design. The dot-dash broken lines in the drawings define the boundaries of the claimed design and form no part thereof.

1 Claim, 6 Drawing Sheets
